MECHANISM FOR KNITTING RUNPROOF OR
RUN-RESISTANT KNITTED FABRICHerbert V. W. Scott, Glen Ridge, N. J., assignor
to Van Raalte Company, New York, N. Y., a
corporation of New York

Application December 15, 1932, Serial No. 647,365

17 Claims. (Cl. 66—135)

This invention relates to mechanism for knitting run-proof or strongly run-resistant knitted fabric, and is an improvement upon, and constituted a continuation as to common subject 5 matter of, my co-pending application Ser. No. 628,391, filed August 11, 1932.

In order to make clear the principle of my invention, I have in the accompanying drawings shown one form of means for practising my invention and particularly for applying certain increased tension to those warp threads which are being incorporated into and form a part of those needle wales which are engaged by the narrowing points in effecting the leg narrowings.

15 In the drawings:

Fig. 1 is a blank from which the full-fashioned stocking is made;

Fig. 2 is a side elevation of the completed stocking;

20 Fig. 3 is a plan view of a portion of the fabric at the narrowings, said view corresponding exactly to a photograph of a fabric made by a microscopic camera;

Fig. 4 is a front elevation of the right hand 25 end portion of the well known Reading machine having my invention applied thereto;

Fig. 5 is an end elevation of said mechanism;

25 Figs. 6, 7 and 8 are respectively a plan view, a front elevation, and a rear elevation of part of 30 the means for throwing additional or warp thread fingers in groups out of action to effect shaping or fashioning of the fabric;

Fig. 9 is a front elevation of that part of the mechanism shown at the upper portion of Fig. 4 35 and representing one form of means to apply additional tension to those warp threads that are contained in those needle wales, stitches whereof are being or are to be laterally transferred by the narrowing points;

40 Fig. 10 is a detail in vertical section of the tensioning rod or means;

Fig. 11 is a front elevation similar to Fig. 9 but showing a somewhat modified means for applying tension to the said warp threads;

45 Fig. 12 is a vertical section of the structure of tensioning means shown in Fig. 11;

Figs. 13 and 14 are respectively a plan view and 50 a front elevation of means for moving the narrowing point bars by which the additional tensioning means is controlled;

Fig. 15 is a vertical section upon an enlarged scale taken through the knitting instrumentalities to show their relative position.

Except for means for applying an additional 55 tension to those warp threads which pertain to

needle wales, stitches whereof are taken by the narrowing points and laterally transferred, the mechanism may be and desirably is the same or substantially the same as that shown in my said application Ser. No. 628,391, and the fabric made 60 by said mechanism is the same as that made by the mechanism of my said application.

In my said application I have disclosed and claimed means for transferring at narrowings stitches composed of a main knitting thread and 65 warp threads. All the warp threads of the fabric are disclosed as under tension in my said application, by means of weights applied to the warp beams.

I have discovered in the course of my experiments that the best effects are secured by applying an increased or subsidiary or additional tension, at the time of making the said transfers or narrowings, to all of those warp threads which pertain to needle wales entered by the narrowing 70 points, and transferred by the action of those points. In making lateral transfers of any full fashioned fabric, the points, having penetrated the stitches or loops and rising therewith, tend slightly to lift the structure of the fabric from 75 the plane of the rest of the fabric. This tends to interfere somewhat with the tension upon those warp threads which pertain to the needle wales, stitches whereof are penetrated by the transfer points. Accordingly I apply additional tension 80 to all of said warp threads which pertain to needle wales whose stitches are transferred by narrowing points, and I preferably provide such additional tension only at the time of such narrowing operation, although my invention is not restricted to 85 applying the additional tension only at such time.

I will therefore describe the general structure of the fabric and so far as necessary the general operation of the mechanism which is common to this application and to my said application Ser. 90 No. 628,391, and will then describe the application thereto of additional tensioning means for the purpose stated.

The mechanism of my invention may be applied to various types of full fashioned knitting 100 machines, but I have represented herein its application to the well known Reading machine without limiting the same thereto.

The full fashioned hosiery to which my invention relates, is run-proof or very strongly run-resistant in both directions throughout the entire extent of the hosiery.

The machine is in practice provided with the usual number of sections upon each of which is knitted a stocking leg and the heel tabs and the 105 110

instep of the foot, so as to make an English type of foot, but my invention is not restricted in this respect. I have in the drawings shown only a single section of the machine, but it is to be understood that each section of the Reading or other type of machine has my invention applied thereto.

Any suitable hosiery yarn or thread may be employed as the main knitting yarn or thread as, for example, silk, artificial silk, rayon, cotton or wool, and I shall use the words "main thread" broadly to include any such type of thread or others that may be suitable. The main thread may be changed from time to time in knitting the stocking as may be necessary, as, for example, at the end of the welt and in the foot. It will be understood that reinforcing threads may be introduced at desired points, in accordance with practice, particularly in the high splice and in the heel tabs, as well as in the sole and at the toe.

The additional, secondary or warp threads may also be of any suitable material, but they are preferably of silk, and as an important purpose of my invention is to provide a run-stop or strongly run-resistant stocking, the stockings whereof, so far as the main thread is concerned, are of usual character, I preferably in each instance use additional threads which are of the same character as the main thread, thus giving a uniform structure and appearance to the resulting hosiery, and one which will not be objected to by those who prefer hosiery having the normal or usual stitch so far as the main thread is concerned.

It will be evident that inasmuch as both the main knitting thread and all the warp and additional threads are of the same character (as, for example, real silk), the necessary or inevitable slight difference in thickness of the main knitting thread at different parts of the length due to any cause, will be overcome or neutralized or very greatly minimized by reason of the presence of the said warp or additional threads in the respective needle wales of the main thread, inasmuch as the same inevitable inequalities would be present in the said warp and additional threads, and therefore the general effect will be more or less an equalization or distribution of the said inequalities so as to make them substantially non-observable.

The needles are desirably spring beard needles but are merely diagrammatically indicated at 1 in Figs. 7 and 8. Sinkers, dividers and knocking over bits are provided as usual, and the mechanism functions as in that type of full fashioned hosiery machines to which my invention is applied, whether it be a Reading hosiery machine or any other type.

Before proceeding to describe the mechanism for practising my invention, I will describe the fabric thereof. In Figs. 1 and 2, the top welt of the full fashioned stocking is indicated at 5, and it will be understood that the additional or warp threads of which there is one for each needle wale of the fabric, and are each confined thereto as fully disclosed in my said application, are indicated at 6 in Fig. 3. These warp threads may be introduced into the fabric from the commencement thereof (that is, at the very commencement of the welt), or the welt may be made in the usual manner and turned or closed, and thereupon a lighter main knitting thread may be substituted. At the same time the additional or warp threads 6 may be introduced and their feeding continued throughout the fabric, as will be described in detail. In Figs. 1 and 2, the leg of the stocking is represented at 7. The ankle or lower calf por-

tion is shaped or fashioned. This is preferably done as follows, reference being particularly made to Figs. 1 and 2.

As hereinafter described in detail, I provide a warp thread finger for each individual warp thread, so that each warp thread is introduced to one needle wale only and at all times is restricted thereto. Instead of mounting the warp thread fingers in pairs or singly for movement into and out of functioning position, I mount the fingers in a series of blocks (preferably five), namely, a long central block carrying those fingers which at all times remain in action, two shorter blocks at either side thereof carrying those fingers which during the course of the knitting introduce the warp threads into the heel tabs, and which blocks are at the proper time moved out of action, preferably manually, and two other blocks, one at either end of the needle series, carrying those warp fingers that introduce the warp threads at the selavage portions of the fabric (that is to say, to so much of the sides of the fabric blank as may be comprehended within the fashioning or narrowings).

Upon reference to Fig. 1, it will be observed that the knitting of the fabric is continued of full width down to the transverse line 8—8 and that then the knitting is abruptly terminated upon certain of the needles. Those needles upon which the knitting is thus terminated are the needles whose warp fingers are carried by the outermost blocks, one at either end of the entire row or series of warp thread fingers. Nevertheless the stitches are transferred inward as indicated in Fig. 1 at 9—9 by means of narrowing points, which may be of the usual number at each side or edge of the blank. Each stitch is transferred inward to the extent of one or two needles, but desirably not more than two, but the traverse of the main thread carrier is continued for the full width of the fabric down to the line 8—8. Inasmuch as the warp threads 6 introduced by the fingers of the two endmost blocks, remain in action because the blocks are not as yet moved into non-functioning position, it will be evident that the warp threads continue to be supplied to the same identical needles as before, although certain stitches are laterally shifted inward, as indicated at 9. The result, however, is to provide an inclined line of small openings 10 along each side of the fabric from a transverse line 11—11 down to the transverse line 8—8. In Fig. 3, I have exactly represented this structure of the fabric, and it will be observed that each of said openings 10 is traversed by at least one warp thread, such threads becoming at once incorporated in the further knitting of the fabric in the triangular portions 12—12 shown in Fig. 1. After the knitting of the entire blank has been completed I trim off each edge along the line of holes 10—10. This leaves entirely acceptable edges because of the non-run character of the fabric, and the two inclined edges are then seamed together in the customary manner and will show the two lines 9—9 of transferred stitches at each side of the seam.

I find that in practice it is desirable to narrow or fashion by transferring stitches to the extent of one needle only, because this lessens the distance that the warp threads are displaced from their normal position, to which normal position they at once return, as elsewhere set forth herein. It will be observed that in the right hand side of Fig. 3 appear several of the actual narrowings, the same being also indicated in Fig. 1.

When the knitting has progressed to the line 8—8, the transverse reciprocation of the main thread carrier is reduced in an automatic manner, not herein necessary to refer to, so that the 5 traverse terminates at the points 13—13 of Fig. 1, and thereafter the fabric is knitted parallel sided excepting as will be described. At the termination of the heel tabs the traverse of the main thread carrier is further reduced by the same 10 means.

It will be understood that the stocking blank will be seamed along all selvage edges, and also at usual points for an English type of foot, to which type my invention is not restricted.

15 The instep or top of the foot portion of the stocking is represented at 14, and it will be understood that my invention is of peculiar advantage with the so-called English type of foot, because the additional warp threads 6 continue 20 without interruption from the top of the stocking down the leg and instep to the toe 15. The heel tabs are indicated at 16—16 and at their inner edges are separated from the instep fabric, as represented most clearly at 17—17, Fig. 1. The 25 high splice portions are indicated at 18—18, and are provided by the usual additional traversing thread carriers for the reinforcing threads, and the movements of such additional thread carriers are controlled in usual manner. The sole portions 30 of the stocking blank or foot are indicated at 19—19, and the toe portion 15 is provided with customary narrowings 20. Narrowings are also provided in the heel tabs as represented at 21 in Fig. 1, and in the sides of the foot adjacent to the 35 heel tabs as represented at 22 in Fig. 2.

It will be understood that the stocking represented in said Fig. 2 is seamed along both sides of the foot as indicated at 23 and also along the bottom of the foot as indicated at 24.

40 It will be understood that each additional or warp thread 6 is introduced to all the loops of its own needle wale only. Each warp thread 6 lies in parallelism with the loop of the main knitting thread 25 of Fig. 6 inside such loop and is so uniformly positioned with respect thereto because of 45 the equality of the tension of the main knitting thread and the additional or warp threads, that the fabric and its constituent threads all lie in an even, uniform and equal tension. Therefore, 50 the fabric is as readily expansible as any knitted fabric and is as expansible longitudinally as any knitted fabric is longitudinally expansible. In other words, the incorporation of the additional or warp threads 6, needle wale for needle wale, 55 does not decrease the expansibility of the fabric nor are the additional threads observable, except by a microscopic or similar examination, especially when the main knitting thread 25 and the additional or warp threads 6 are of the same texture, color and character as is desirable. The 60 warp threads 6 do not enter into or become incorporated in the sinker wales, and their presence in the needle wales prevents a run in those needle wales, inasmuch as the additional or warp threads 65 extend lengthwise the wales, whereas the main knitting thread extends transversely of the wales.

It will be understood that the fabric is knitted as rapidly as a fabric with plain loops is knitted of only a main thread.

70 In Figs. 4 to 8 inclusive, I have represented sufficient of the general mechanism of my invention and its adaptation to the well known Reading type of machine to make the same entirely clear. In Fig. 4, I have represented one end portion 75 only of a Reading type of full fashioned knit-

ting machine, and that merely sufficiently to show the application of my invention to one section thereof, but it is to be understood that all the sections of the machine, whether it be a legger or a footer, are provided with means for properly introducing the warp threads each into one needle wale of the fabric.

80 Referring to Figs. 4 and 5, a horizontal portion of the framing is indicated at 26. Upstanding therefrom and suitably bolted thereto at each end of the machine frame, there is a bracket 27 and at the inner or left hand end of the first section and at a corresponding place for each section except the endmost section at the left, there is an upright 28 similarly bolted to the frame 26. Adjacent uprights 27, 28 are connected together by a suitable tie rod 29, and this structure is repeated throughout the machine.

85 I preferably provide the following mechanism for introducing the warp threads to the individual fingers, one for each knitting needle.

90 A shaft 30 is supported in the upright 27, 28, and extends the entire length of the machine. Upon that portion of the shaft between each two next adjacent uprights I provide in this embodiment of the invention five warp spools indicated at 31, 32, 33, 34, 35. These spools are all loose upon the shaft 30, but are restrained from rotation by the means to be described. The 95 length of the said spools corresponds to the length 100 of the respective blocks in which are mounted the warp thread fingers, said blocks being indicated at 36, 37, 38, 39, 40, in Figs. 7 and 8. Upon each end of each spool is a flange 41, and as shown clearly in Figs. 4 and 5, a series of 105 cords 42 having weights 43 at their lower ends are passed about or lie in contact with a sufficient part of the periphery of said flanges to retard or restrain their feeding movement. The 110 cords 42 are all secured as indicated at 44 at the 115 top of the framing. The individual warp threads are wound upon the respective spools and feed off therefrom during the knitting operation.

120 A suitable tensioning means for all the warp threads 6 (but additional to which I provide tensioning means for those warp threads that participate in the transfer or narrowing operations) is represented in Figs. 4 and 5. Therein is represented a friction bar 46 of suitable length, one for each section of the machine, which is supported for suitable transverse play in a slot 47 in each of the necessary uprights. About said 125 rod 46 is passed a cord 48 that extends over a small roll or drum 49 and is weighted at its end as indicated at 50. The said warp threads on 130 their way to the individual fingers pass through suitable openings 51 in a plate 52. In this way, a suitable tension is maintained about all the 135 warp threads (except as hereinafter described with respect to the warp threads near the selvage edges of the fabric) and is maintained the same as the tension upon the main knitting thread, which is desirably tensioned by the means shown in my said application Ser. No. 628,391, and which need not be herein described or illustrated.

140 The main thread carrier is of the same type as that shown in my said application, and is operated in the same way. The warp thread fingers are indicated diagrammatically at 60 in Figs. 7 and 8, and may be and desirably are of the same 145 character as shown in my said application. The narrowing points are represented at 61 and the same are also of the same character as disclosed in my said application. The warp thread fingers 60 are rigidly mounted in the several blocks 36, 150

37, 38, 39, 40, all of which are secured to longitudinally extending members 62, 63, supported by collars 64, 65, upon a longitudinally extending rod or shaft 66. The structure is such that the 5 blocks 36, 37, 39, 40, may be swung, preferably manually, sufficiently outward to withdraw their warp threads from the corresponding needles. The blocks 36, 40 are so swung into non-functioning position when the knitting has proceeded 10 down to the transverse line 8—8 of Fig. 1, and the blocks 37, 39 are similarly swung out of functioning position when the knitting has progressed down to the end of the heel tabs 16, 16 of Fig. 1. I provide bars 71, 72 extending the entire length 15 of the machine or one half the length thereof, by swinging which in one direction or the other the blocks 36, 40, throughout the entire machine, may at one time be swung into non-functioning position and at another time the blocks 37, 39 may 20 be swung into non-functioning position.

It is unnecessary to describe or illustrate in detail the means by which the support for the warp fingers 60 is moved to pass or wrap each warp thread about its proper needle, at the 25 proper time. Each warp thread guide in effect, in this embodiment of my invention, makes a substantially rectangular movement about its own needle, but this movement may be varied within the scope of my invention in any suitable 30 way that effects the introduction of each warp thread into each stitch or loop of its own needle wale.

The narrowing points 61 are moved in the manner shown in my said application Ser. No. 628,391 35 to effect the transfer of stitches, such movement being automatic and controlled as set forth in said application.

It will be understood that the timing of the movements of the warp thread fingers 60 and of 40 the main thread carrier is the same as that shown and described in my said application Ser. No. 628,391. The traverse of the main thread carrier starts substantially simultaneously with the commencement of the thread laying operation 45 of the warp thread 6. The knitting needles commence their descent immediately after each course of the main knitting thread is laid.

In order to impart both axial movement and a 50 rocking movement to the rod or shaft 66, I preferably employ the same means as shown in my said application Ser. No. 628,391.

Against one end of said rod or shaft 66 takes the inclined end 75 of a vertical spindle or shaft 76 mounted to be moved axially in a guide or bearing 77. The shaft 76 has pivoted thereto an 55 upright link 79 which at its lower end is slotted as indicated at 80 and is there secured by a pin 81 to a lever arm 82 pivoted at 83 in the framing and normally held downward by a suitable spring 84. Upon said lever arm 82 is a roll 85 resting 60 upon a cam 86 fast upon the main cam shaft 87. Said cam 86 is provided with a projection 88 that rides under the roll 85 and at the proper time lifts the upright shaft or rod 76 so as to impart axial movement to the rod or shaft 66. Said rod 66 is moved in the opposite direction by 65 a suitable spring.

In order to impart suitable rocking movement 70 to the rod or shaft 66 so that each warp thread finger 60 may describe a suitable substantially rectangular path about its corresponding needle, said shaft 66 has fast thereon a link 89 which is secured preferably removably by a pin 90 to an upright bar or member 91. Said bar or member has at its lower end a roll 92 resting upon

the periphery of a cam 93 having a concavity 94 controlling the up and down movements of said member 91, consequently controlling the rocking movement of the rod or shaft 66. The timing of the parts is such, and the relative location of the point or projection 88 and the concavity 94 are such, that the proper rectangular movements are given to the warp thread guides 60. Upon the main cam shaft 87 is a suitable cam 95 upon the periphery whereof rests a roll 96 upon a lever arm 97 pivoted also at 83. Pivotedly connected to the lever arm 97 is an upright link 98 which at its upper end is secured to the rod or bar 100 that supports the narrowing point structure.

I have stated that I provide means for applying tension, at the time of the lateral transfer of loops for the leg narrowings to those warp threads only which are involved in such transfer or narrowing by reason of the fact that they are incorporated in the needle wales, loops of which are being laterally transferred. I have in Figs. 9 and 10 represented one form of means for so applying tension. In Fig. 9, I have represented the two narrowing bars at 101, 102. The means for operating said bars are preferably the usual 100 means for imparting movements to the narrowing bars of the Reading machine or other type of machine to which my invention is applied. I have therefore in Figs. 13, 14, represented in plan and in front elevation the narrowing bars and 105 the means for operating the same which I will briefly describe.

The said bars 101, 102, are respectively connected to nuts 103, 104, upon the oppositely threaded portions 105, 106 of the shaft 107, which 110 by means of the ratchets 108 and 109 is turned in opposite directions at the proper time automatically. A holding wheel 110 is also provided upon said shaft 107.

Referring again to Figs. 9 and 10, there are 115 fast upon the narrowing bars 101, 102 respectively, the upright brackets 111, 112 that preferably have adjusting joints 113, 114, by which the angle of the upper ends or parts may be altered if desired to accommodate them to a different position of the guide rod 115 which is suitably mounted in the upright members of the framing and over which all of the warp threads pass as indicated in Fig. 10. The said rod may be adjusted in the framing by positioning the same in any of the openings 116, and if so adjusted the upper portions of the uprights 111, 112 120 would be adjusted at their joints, in conformity with the changed position of the rod 115.

Loosely mounted upon said rod 115 so as to rock thereon under the influence of their own weight and also so as to be slid lengthwise thereon by means of the uprights 111, 112, are two brackets 116, 117 carrying short rods 118, 119 preferably headed as shown at 120, 121. The hubs of the said brackets 116, 117 are circumferentially grooved as indicated at 122, 123 to be engaged by the upper ends of said uprights 111 and 112, so that as the narrowing bars 101 and 102 are moved toward each other in the narrowing operation, the tension rods 118, 119 are correspondingly moved toward each other.

I have not attempted to show all the warp threads which at any time are tensioned by said rods 118, 119, but it is to be understood that the purpose of said rod is to apply a preferably light additional tension to all of those warp threads which pertain to needle wales at or near the selvages, loops of which are being entered by the narrowing points to effect the described narrow-

80

145

150

ings as illustrated in Fig. 3. The amount or extent of the said tension is determined by the weight of the said rods 118, 119, and their supporting brackets 116, 117.

- 5 In Fig. 9 I have indicated by the brackets A, B the warp threads that receive the additional tension, but as stated I have not here attempted to show the exact or even approximate number of said warp threads. All the other warp threads 10 pass only over the rod 115 and certain of these other warp threads I have indicated in Fig. 9 at C. All the warp threads pass over the said rod 115.

In Figs. 11 and 12, I have shown a slightly modified arrangement, but I have in said figures used the same reference characters, but have designated them as 111', 112', etc.

In addition to the structure shown in Figs. 9 and 10, I have in Fig. 11 provided an additional guide bar 124 over which are passed only those warp threads that do not receive the additional tension by the means already described.

My invention is not limited to any construction wherein a primary tension is provided for all the warp threads, for although I prefer to apply a primary tension to all the warp threads, my invention is particularly concerned to applying a tension to those warp threads pertaining to needle wales, loops of which are acted upon in the narrowing operation. The heads 120, 121 are preferably provided so as to prevent any of the warp threads from slipping off the rods 118, 119.

Having thus described one illustrative embodiment of the invention, it is to be understood that although specific terms are employed, they are used in a generic and descriptive sense and not for purposes of limitation; the scope of the invention being set forth in the following claims.

I claim:

- 40 1. In a full-fashioned hosiery knitting machine having spring beard needles and cooperating sinkers, etc. to form successive courses of regular loops of a main knitting thread; main thread carrier means to traverse said main thread from edge to edge of the hosiery blank and including means to shorten said traverse at the termination of the leg narrowings; warp thread guiding fingers to introduce separate warp threads into the needle wales of the fabric coincidently with the laying of the respective courses of the loops of the main knitting thread; means to support said fingers in a series of a relatively small number of groups, whereof the middle group is constantly in operation, and whereof the two end groups may be moved into non-feeding position, and means for laterally shifting or transferring inward stitches of the main knitting thread and the correlated warp threads at substantially the usual narrowing points, and means to apply tension pertaining only to those warp threads at or near the selvages whose needle wales participate in the act of transferring or shifting loops at the leg narrowings.

- 65 2. In a full-fashioned hosiery knitting machine having spring beard needles and cooperating sinkers, etc. to form successive courses of regular loops of a main knitting thread; main thread carrier means to traverse said main thread from edge to edge of the hosiery blank; warp thread guiding fingers to introduce separate warp threads, one into each needle wale of the fabric, coincidently with the laying of the respective courses of the loops of the main knitting thread; means laterally to transfer or shift loops of the main and warp threads inward at substantially

the leg narrowing positions, and means to apply tension pertaining only to those warp threads at or near the selvages whose needle wales participate in the act of transferring or shifting loops at the leg narrowings.

3. In a full-fashioned hosiery knitting machine having spring beard needles and cooperating sinkers, etc. to form successive courses of regular loops of a main knitting thread; main thread carrier means to traverse said main thread from edge to edge of the hosiery blank; warp thread guiding fingers to introduce separate warp threads, one into each needle wale of the fabric, coincidently with the laying of the respective courses of the loops of the main knitting thread; means laterally to transfer or shift loops of the main and warp threads inward at substantially the leg narrowing positions; means for manually moving into non-feeding position one or more groups of said fingers during the knitting of the blank; and means to apply tension pertaining only to those warp threads at or near the selvages whose needle wales participate in the act of transferring or shifting loops at the leg narrowings.

4. In a full fashioned hosiery knitting machine having spring beard needles and cooperating sinkers, etc. to form successive courses of regular loops of a main knitting thread; main thread carrier means to traverse said main thread from edge to edge of the hosiery blank; warp thread guiding fingers, one for each needle wale, to introduce a separate warp thread into each loop of each needle wale of the fabric coincidently with the laying of the respective courses of said loops; narrowing points adjacent each selvage portion of the fabric and means to move the same toward each other to transfer or shift loops of the main thread and correlated warp threads, thereby to provide two opposite inclined lines along which the fabric outside thereof may be subsequently trimmed, and means to apply tension pertaining only to those warp threads at or near the selvages whose needle wales participate in the act of transferring or shifting loops of the leg narrowings.

5. In a full fashioned hosiery knitting machine having spring beard needles and cooperating sinkers, etc. to form successive courses of regular loops of a main knitting thread; main thread carrier means to traverse said main thread from edge to edge of the hosiery blank; warp thread guiding fingers which in number sufficiently approximate the number of needle wales so as to render the fabric of a non-run or strongly run-resistant character by reason of the introduction of warp threads into the fabric coincidently with the laying of the respective courses of said loops; means to support said fingers in a series in a small number of groups; means separately to support the warp threads for the respective small number of groups; means separately to tension the support for each of said several groups of warp threads; and means to apply tension pertaining only to those warp threads at or near the selvages whose needle wales participate in the act of transferring or shifting loops at the leg narrowings.

6. In a full-fashioned hosiery knitting machine having spring beard needles and cooperating sinkers, etc. to form successive courses of regular loops of a main knitting thread; main thread carrier means to traverse said main thread from edge to edge of the hosiery blank; warp thread guiding fingers which in number sufficiently approximate the number of needle wales so as to

render the fabric of a non-run or strongly run-resistant character by reason of the introduction of warp threads into the fabric coincidently with the laying of the respective courses of said loops; 5 means to support said fingers in a series in a small number of groups; means separately to support the warp threads for the respective small number of groups; means separately to tension the support for each of said several groups of warp threads; means for separately manually throwing out of operation small end groups of said series of fingers; and means to apply tension pertaining only to those warp threads at or near the selvages whose needle wales participate in the 10 act of transferring or shifting loops at the leg narrowings.

7. In a full-fashioned hosiery knitting machine having knitting needles and cooperating sinkers, etc. to form successive courses of regular loops 20 of the main knitting thread; main thread carrier means to traverse said main thread from edge to edge of the hosiery blank; warp thread guiding fingers to introduce separate warp threads into different needle wales of the fabric coincidently with the laying of the respective courses 25 of the loops of the main knitting thread; means laterally to transfer or shift loops composed of the main and warp threads inward at substantially the leg narrowing positions; and means to apply tension pertaining only to those warp threads at or near the selvages whose needle wales participate in the 30 act of transferring or shifting loops at the leg narrowings.

8. In a full-fashioned hosiery knitting machine 35 having knitting needles and cooperating sinkers, etc. to form successive courses of regular loops of a main knitting thread; main thread carrier means to traverse said main thread from edge to edge of the hosiery blank; warp thread guiding fingers to introduce a series of warp threads 40 into different needle wales of the fabric coincidently with the laying of the respective courses of said loops; narrowing point adjacent each selvage portion of the fabric; means to move the 45 same toward each other to transfer or shift loops composed of the main thread and correlated warp threads, thereby to provide two opposite inclined lines along which the fabric outside thereof may be subsequently trimmed; and means to apply tension 50 pertaining only to those warp threads at or near the selvages whose needle wales participate in the act of transferring or shifting loops at the leg narrowings.

9. In a full-fashioned hosiery knitting machine 55 having knitting needles and cooperating sinkers, etc. to form successive courses of regular loops in the main knitting thread; main thread carrier means to traverse said main thread from edge to edge of the hosiery blank; warp thread guiding fingers, one for each needle wale, to introduce a separate warp thread into each loop of each 60 needle wale of the fabric coincidently with the laying of the respective courses of said loops; means to support said fingers in a series in a 65 small number of groups; means separately to support the warp threads for the respective small numbers of groups; narrowing points adjacent each selvage portion of the fabric; means to move said narrowing points toward each other to transfer or shift loops composed of the main thread and the correlated threads, thereby to provide two 70 oppositely inclined lines along which the fabric outside thereof may be subsequently trimmed; and means to apply tension pertaining only to 75 those warp threads at or near the selvages whose

needle wales participate in the act of transferring or shifting loops at the leg narrowings.

10. In a full-fashioned hosiery knitting machine having spring beard needles and cooperating sinkers, etc. to form successive courses of regular loops of a main knitting thread, main thread carrier means to traverse said main thread guide from edge to edge of the hosiery blank, but including means to traverse the same the full width of the fabric past all the leg narrowings and then abruptly to shorten said traverse to substantially the space between the lower ends of the two lines of narrowing marks or openings; warp thread guiding fingers to introduce separate warp threads one into each needle wale of the fabric coincidently with the laying of the respective courses of the loops of the main knitting thread; means laterally to transfer or shift loops composed of the main knitting thread and correlated warp threads inward at substantially the leg narrowing positions; and means to apply tension pertaining only to those warp threads at or near the selvages whose needle wales participate in the 80 act of transferring or shifting loops at the leg narrowings.

11. In a full-fashioned hosiery knitting machine having spring beard needles and cooperating sinkers, etc. to form successive courses of regular loops of a main knitting thread, main thread carrier means to traverse said main thread guide 85 from edge to edge of the hosiery blank, but including means to traverse the same the full width of the fabric past all the leg narrowings and then abruptly to shorten said traverse to substantially the space between the lower ends of the two lines 90 of narrowing marks or openings; warp thread guiding fingers to introduce separate warp threads into different needle wales of the fabric respectively coincidently with the laying of the respective courses of the loops of the main knitting 95 thread; means laterally to transfer or shift loops composed of the main knitting thread and correlated warp threads inward at substantially the leg narrowing positions; and means to apply tension pertaining only to those warp threads at or 100 near the selvages whose needle wales participate in the act of transferring or shifting loops at the leg narrowings.

12. In a full-fashioned hosiery knitting machine having upright spring beard needles and cooperating sinkers, etc. to form successive courses of regular loops of a main knitting thread; main thread carrier means mounted at one side of the needle series and adapted to be traversed from edge to edge of the hosiery blank; 110 warp thread guiding fingers to introduce separate warp threads, one into each needle wale of the fabric, coincidently with the laying of the respective courses of the loops of the main knitting thread; said warp thread guiding fingers 115 being mounted at the opposite side of the knitting series from said thread carrier, so as to depend into position adjacent to the needles so as to be moved between said needles to lay their threads; narrowing points for insertion into loops to effect lateral transfer thereof; means to operate said points so as to provide inclined lines of indicating openings at the leg narrowing zone as a guide for trimming off fabric laterally beyond said openings; and means to apply tension pertaining only to those warp threads at or near the 120 selvages whose needle wales participate in the act of transferring or shifting loops at the leg narrowings.

13. In a full-fashioned hosiery knitting ma- 125

- chine having upright spring beard needles and cooperating sinkers, etc. to form successive courses of regular loops of a main knitting thread; main thread carrier means mounted at one side of the needle series and adapted to be traversed from edge to edge of the hosiery blank; warp thread guiding fingers to introduce separate warp threads, one into each needle wale of the fabric, coincidently with the laying of the respective courses of the loops of the main knitting thread; said warp thread guiding fingers being mounted at the opposite side of the knitting series from said thread carrier so as to depend into position adjacent to the needles so as to be moved between said needles to lay their threads; means laterally to transfer or shift loops composed of the main knitting thread and correlated warp threads inward at substantially the leg narrowing positions, and means to apply tension pertaining only to those warp threads at or near the selvages whose needle wales participate in the act of transferring or shifting loops at the leg narrowings.

14. In a full-fashioned hosiery knitting machine having knitting needles and cooperating sinkers, etc. to form successive courses of regular loops of the main knitting thread; main thread carrier means to traverse said main thread from edge to edge of the hosiery blank; warp thread guiding fingers to introduce separate warp threads into different needle wales of the fabric coincidently with the laying of the respective courses of the loops of the main knitting thread; means to apply tension to all said warp threads; means laterally to transfer or shift loops composed of the main and warp threads inward at substantially the leg narrowing positions; and means to apply an additional or subsidiary tension to those warp threads pertaining to needle wales at or near the selvages, loops whereof are transferred or shifted inward at the leg narrowings.

15. In a full-fashioned hosiery knitting machine having knitting needles and cooperating sinkers, etc. to form successive courses of regular loops of the main knitting thread; main thread carrier means to traverse said main thread across the hosiery blank; warp thread guiding means to introduce separate warp threads into the needle wales of the fabric coincidently with the laying of the respective courses of the loops of the main knitting thread; means to support said means in a series of groups, whereof the middle group is constantly in operation, and whereof end groups may be moved into non-feeding position, and means for laterally shifting or transferring inward stitches of the main knitting thread and the correlated warp threads at desired points, and means to apply tension pertaining only to those warp threads at or near the selvages whose needle wales participate in the act of transferring or shifting loops.

HERBERT V. W. SCOTT.
